UNITED STATES PATENT OFFICE.

WILLIAM C. BOSENBURY, OF RICHMOND, INDIANA, ASSIGNOR TO STARR
PIANO COMPANY, OF RICHMOND, INDIANA.

PEDAL-ACTION FOR GRAND PIANOS.

SPECIFICATION forming part of Letters Patent No. 755,102, dated March 22, 1904.

Application filed April 6, 1901. Serial No. 54,705. (No model.)

To all whom it may concern:

Be it known that I, WILLIAM C. BOSENBURY, a citizen of the United States, residing at Richmond, in the county of Wayne and State of Indiana, have invented new and useful Improvements in Pedal-Actions for Grand Pianos, of which the following is a specification.

This invention relates to pedal-actions for musical instruments; and it is especially adapted for use on grand pianos, substantially as herein set forth and shown.

The object of this invention is to provide a simple and positive mechanism for controlling by their respective pedals the sostenuto, the pianoforte loud, and the soft action of a piano, such as described. I attain these and other objects, which will appear from the mechanism illustrated in the accompanying drawings, forming a part of this specification, in which—

Figure 1 represents my mechanism attached to the under side or bottom of a grand piano, being a plan view of my mechanism as though seen from above through the bottom of the piano. Fig. 2 is a rear view of the lyre of a grand piano, showing my improvements in connection therewith. This figure is taken from line X X of Fig. 1. Fig. 3 is a side view of the lyre of a grand piano, showing my improvements in connection therewith. This figure is taken from the line Y Y of Fig. 1. Fig. 4 is a detail view in front elevation of a part of the soft-pedal mechanism, showing the mode of attachment and operation. Fig. 5 is an end view of the part shown in Fig. 4 and taken from the line V V of that view. Fig. 6 is a detail side view of a part of the loud-pedal mechanism. Fig. 7 is a detail cross-section of the parts shown in Fig. 6 and taken on the line Z Z of that view. Fig. 8 is a sectional plan view of the pedals of a piano, taken from the line U U of Fig. 2. Fig. 9 is a detail side view of a part of the sostenuto mechanism.

Similar letters and figures of reference refer to similar parts throughout the several views. The letters of reference refer to the parts that are old, and the figures of reference refer to the parts that are new in the drawings and specification.

Referring now to the drawings, A repre-

sents the under side or bottom of a grand piano.

B represents the lyre as used in connection with a piano.

C represents the turned posts connecting the lyre with the bottom of the piano and suspending the lyre a short distance from the floor of the room in which it is contained.

Referring now to the essential parts, 50' represents the left-hand pedal, which operates the soft or low action of the piano.

50" represents the center pedal, or that pedal which operates the sostenuto.

50" represents the right-hand pedal, or that pedal which operates the loud mechanism of a piano.

51 represents cross-hatching on the outer upper face of all the pedals just referred to. This not only adds to the appearance of the pedals, but it presents a rough surface which comes into contact with the foot of the operator, thus preventing the foot of the operator from slipping off the pedal.

52', 52", and 52" represent cupped-shaped depressions on the inner ends of all three of the pedals for the purpose which will herein-after appear.

53 represents cartridge-shaped members, one of each attached to each end of the rods 54', 54", and 54"". The rounded ends of 53 are adapted to work in the cup-shaped depressions 52', 52", 52"', 58', 58", and 58"".

54', 54", and 54"" represent rods, each end of which is supplied with the one of the members 53 connecting the pedals 50', 50", and 50""", respectively, to their respective mechanism secured to the bottom of the piano.

55 represents the pivots on which the pedals operate, as shown most clearly in Fig. 3 and Fig. 8.

56 represents hangers or brackets used interchangeably and in pairs for the purpose of pivotally mounting various parts of my mechanism to the bottom of the piano.

57 represents common screws adapted to pass through holes or slots provided in the parts 60, 61, and 62 for that purpose and then screwed into the bottom of the piano. The purpose of said screws is to act as guides and

to prevent said parts 60, 61, and 62 from dropping farther down than is desired.

58', 58", and 58''' represent cup-shaped depressions on the parts 60, 61, and 62, respectively, for the purpose of engaging the parts 53 on the upper ends of the rods 54', 54", and 54''', respectively, and are of like shape and form as 53.

60 represents a lever operated by the pedal 50' for controlling the soft or mild tone of the pianoforte by means of the point of 60, (represented by 60').

61 represents a double-armed lever operated by the pedal 50" for controlling the sostenuto of the pianoforte.

62 represents a lever operated by the pedal 50''' for controlling the pianoforte loud.

It can now be seen that should the pedal 50' be depressed by the foot of the operator pressing 20 on the cross-hatching 51 on the pedal 50' the rod 54' will be raised endwise, carrying the lever 60 to the position shown by the dotted lines in Fig. 4, which gives the proper action to the part 60' to accomplish the object desired.

25 It is also apparent that should the pedal 50" be depressed by the foot of the operator pressing on the cross-hatching 51 on the pedal 50" the rod 54" will be raised endwise, carrying the lever 61 to the position shown by the dotted lines in Fig. 9, which gives the proper action to the inner mechanism of the piano, and it is also apparent that should the pedal 50''' be depressed by the foot of the operator pressing 30 on the cross-hatching 51 on the pedal 50''' the rod 54''' will be raised endwise, carrying the lever 62 to the position shown by the dotted lines in Fig. 6, which gives the proper action to the inner mechanism of the piano.

40 The extent of the action imparted by the various pedals to the various levers referred to can be controlled and adjusted by means of the screws 57.

I have found it advantageous to cross-hatch 45 the outer flaring ends of my pedals, as shown particularly in Fig. 8, by the numeral 51. This not only adds to the appearance of the pedal, but it is an actual benefit in that it pre-

vents the foot of the operator from slipping on the pedal.

50 From the foregoing description, taken in connection with the drawings, the operation of this invention will be readily understood, and its many advantages will be fully appreciated, and I will simply state that the invention herein shown and described is by reason of its simplicity, attractiveness, and ease and efficiency of operation a useful and practical invention, as has been fully demonstrated.

60 My improvements as herein shown and described are perfectly adapted to accomplish the results which they are intended to accomplish; but it is evident that changes in and modifications of the construction herein shown and described may be made and that analogous parts may be used to accomplish the same results without departing from the spirit of my invention or sacrificing any of its advantages.

65 Having shown and described the best construction of my improvements to me known at this time, what I claim as new, and desire to secure by Letters Patent of the United States, is—

70 In a pedal-action for pianos, the combination with a pivoted pedal having a cup-shaped recess formed therein, of a lever consisting in part of a body portion, pintles on the ends of said body portion, brackets secured to the under side of the piano adapted to support the 75 lever by the pintles, oppositely-curved arms extending out from near the ends of said body portion, one of said arms provided with a slot and both provided with recesses, a vertical rod adapted to engage one of said arms 80 and the pedal, the other arm adapted to act as an operating-lever, and a screw engaging said slot and adapted to adjustably limit the downward movement of said arms.

75 In witness whereof I have signed my name 85 to this specification in the presence of two subscribing witnesses.

WILLIAM C. BOSENBURY.
